by Arthur C. Eckert, atty.

UNITED STATES PATENT OFFICE.

FRANK TREUKE, OF HERCULANEUM, MISSOURI.

GRATE-CLEANER.

1,168,443.

Specification of Letters Patent. Patented Jan. 18, 1916.

Application filed September 13, 1915. Serial No. 50,504.

To all whom it may concern:

Be it known that I, FRANK TREUKE, a citizen of the United States, and resident of Herculaneum, State of Missouri, have invented certain new and useful Improvements in Grate-Cleaners, of which the following is a specification, containing a full, clear, and exact description, reference being had to the accompanying drawings, forming a part hereof.

The object of my invention is to design a means of removing clinkers, dross, slag or other materials from moving grates of the sectional chain variety; to prevent the clogging of the grate openings so as to permit air to pass freely through the grate.

My invention finds particular application in smelting operations especially the reduction and purification of lead. In the conventional machine now used in the lead industry, a man must be stationed at a suitable point in the path of the chain grate; by means of pokers and other rods the grate is kept open so that sufficient air is permitted to pass through to bring about the necessary oxidation required by the process. My invention will entirely supplant this operator, will absolutely keep the grate in an operating condition, at a very low initial cost and at a nominal upkeep charge.

With the above and other objects in view, my invention has relation to certain novel features of construction and operation, examples of which are described in the following specification and illustrated in the accompanying drawings in which—

Figure 1 is a fragmental longitudinal sectional elevation of my device. Fig. 2 is a cross-section on the line 2—2 of Fig. 1. Fig. 3 is an enlarged detail plan of a grate section.

In the drawings numerals 4 and 5 designate two stands secured at the sides of the grate section 6.

7 designates a horizontal cross beam connecting the stands 4 and 5 at their upper extremities.

8 designates a cylinder firmly secured to the shaft 9 which is journaled to 4 and 5 at 10 and 11.

12 and 13 represent two guides secured firmly to each grate section.

14 and 15 designate two feet extending from the guides 12 and 13; these feet are supported on tracks (not shown), hence each grate section can be moved on its base on the

track around its endless path (not shown) in drawing.

The lateral surface of cylinder 8 is covered with fin like projections 8', conforming to the openings in the grate section 6, so that when the cylinder 8 and the grate section 6 are in the proper relative position, the projections on the cylinder will engage the grate openings. As the grate sections 65 are moved in their path, the cylinder 8 by frictional contact or otherwise (frictional contact is shown) is caused to revolve thereby causing the projections on the cylinder to stamp or press out the foreign substance that may be lodged in the grate holes.

My preferred form of grate is the herring bone, but the cylinder can be designed for any grate by changing the shape and positioning of the projection 8' on cylinder 8. 75 At certain times, it becomes desirable to adjust the spacing between the cylinder and the grate and sometimes for repairs to raise the cylinder 8 entirely away from the grate; this is accomplished in a very simple manner as follows:—The stands 4 and 5 have vertical slots (not shown) cut in them, the widths of which slightly exceed the diameter of the shaft 9 so that by raising or lowering the shaft in this slot the desired object is 80 attained. To facilitate the moving of the shaft in the slots the arms 16 and 17 are provided; at their lower ends they are fastened to the shaft 9 and at their upper to a horizontal movable member which lies in a slot 90 (not shown) in the upper portion of beam 7. To the center of this horizontal member is secured an eye 18; to the beam 7 is secured the eye 19. The lever 20 by means of a pin 21 is fulcrumed at eye 19 and by means of 95 pin 22 is rotatively secured to the horizontal movable member. It will be readily seen that by moving the lever 20 the cylinder 9 will be moved in a vertical plane in and out of engagement with the grate. To secure 100 the correct lateral positioning of the cylinder 8, springs 23 and 24 are positioned as shown.

What I claim and mean to secure by Letters Patent is—

1. In a device of the character described, a grate, a cylinder having projections, adjustable means, to vary the space between the grate and the cylinder and for bringing the projections of said cylinder into selective engagement with the openings in said grate.
2. In a device of the character described,

a chain grate comprising sections adjacently secured together, a cylinder with projections of substantially the size and positioning as the grate openings, and adjustable means, to vary the space between the grate and the cylinder, and for selectively bringing the grate and cylinder into frictional engagement.

3. In a device of the character described, 10 a chain grate comprising sections adjacently secured together, a cylinder with projections of substantially the size and positioning as the grate openings, shaft stands, said cylinder mounted on said shaft and said 15 shaft rotatively secured to said stands, said stands having vertical slots in which said shaft may move and means for moving said shaft in the slots in said stands.

4. In a device of the character described, 20 a herring bone chain grate, a cylinder with projections on its lateral surface, the cylinder in frictional engagement with the grate so that each projection of the cylinder, engages a certain opening of the grate, thereby 25 causing the clinker in each grate opening to be removed by its companion projection of the cylinder, and means for regulating the pressure of said cylinder against said

grate and for varying the space between the grate and the cylinder. 30

5. In a device of the character described, a herring bone chain grate, a cylinder with projections on its lateral surface, the cylinder in frictional engagement with the grate so that each projection of the cylinder engages a certain opening of the grate, thereby 35 causing the clinker in each grate opening to be removed by its companion projection of the cylinder and means for regulating the pressure of said cylinder against said 40 grate for purposes of cleaning both said grate and said cylinder, comprising shaft stands, a cylinder shaft, said cylinder mounted on said shaft and said shaft rotatively secured to said stands, said stands having vertical slots in which said shaft may move 45 and means for moving said shaft in the slots in said stands, substantially for the purposes set forth.

In testimony whereof, I have signed my 50 name to this specification, in the presence of two subscribing witnesses.

FRANK TREUKE.
